UNITED STATES PATENT OFFICE.

WILLIAM H. MATTHIES, OF HACKENSACK, NEW JERSEY, ASSIGNOR TO WESTERN ELECTRIC COMPANY, INCORPORATED, OF NEW YORK, N. Y., A CORPORATION OF NEW YORK.

STRAIGHTFORWARD TRUNKING SYSTEM.

Application filed July 8, 1925. Serial No. 42,121.

This invention relates to telephone systems and more particularly to an improvement in trunking arrangements for straightforward trunking systems.

5 An object of this invention is to provide a simplified and inexpensive arrangement for trunking at telephone offices whereby a number of smaller offices, instead of as heretofore having individual trunks leading to a distant larger office, may be provided with trunks leading to an adjacent intermediate or centrally located office and having this intermediate office in turn connected to trunks leading to the distant larger office.

15 In this arrangement, the number of trunks out going to the larger office will be less than the total number of trunks incoming to the intermediate office. The advantage of such an arrangement is particularly evident when 20 these offices are located in large cities where underground cable installations between the offices are extremely costly. The longer and therefore more expensive trunk lines between an intermediate and distant office will be 25 few; that is, only a sufficient number of such trunks will be provided to care for the total traffic that is likely to be anticipated between all the smaller offices and the distant office. A considerable saving is thereby effected in 30 the interest charges on investments in cables and a higher efficiency is obtained in the use of the cables provided.

Another object of the invention is to provide in a simplified trunking arrangement of 35 this type an all trunks busy arrangement requiring the minimum amount of apparatus individual to the incoming trunks and a greatly simplified equipment common to the outgoing trunks.

40 To attain these and other objects of the invention, as will hereinafter appear, there is provided at the intermediate office a trunk hunting switch for each trunk line incoming from the smaller offices and automatic circuit arrangements whereby the moment a trunk is seized by an operator at a smaller office, the corresponding switch at the intermediate office will be actuated to hunt for and connect said trunk with an idle trunk 45 leading to the distant larger office.

50 A feature of the invention is the provision in a system of the above type of means whereby a busy test condition will be prepared for all the trunks incoming to the in-

termediate office from the smaller offices 55 when all trunks outgoing therefrom to the larger office are engaged; the arrangement being such that when all such trunks are busy and when an operator at a smaller office attempts to establish a connection by engaging a trunk leading to the intermediate office a busy condition will be applied to that trunk as an indication that all outgoing trunks are engaged.

Another feature resides in means whereby 60 said prepared condition is in the form of a tone on the tip conductor of the incoming trunk or trunks seized after all outgoing trunks are engaged.

Another feature of this invention resides 65 in the provision of means whereby after an all outgoing trunk busy condition is established and another incoming trunk is seized the corresponding switch is actuated to hunt 70 for an idle outgoing trunk and if the incoming trunk is held after one or more of the outgoing trunks become idle this switch continues to hunt for an idle outgoing trunk and when found connects the corresponding incoming trunk therewith.

In the accompanying drawing is illustrated 75 a straight-forward trunking system with the circuit arrangement for one of a plurality of incoming trunks from each of two smaller offices and their corresponding trunk 80 hunting switches at an intermediate office, and also two out of a plurality of trunks outgoing to a distant office. The busy test equipment common to all of these incoming and outgoing trunks is also illustrated in the 85 drawing.

Referring now specifically to the details of the system illustrated in this drawing, the portion marked Office 1 shows two multiple jacks 1 and 2 at two different operator's positions in a smaller office and a trunk line 3 leading to the intermediate office, while the portion marked Office 2 shows the same arrangement at another smaller office; that is, multiple jacks 4 and 5 at two different operator's positions are shown with a trunk line 6 extending therefrom to the intermediate office. At the portion marked "intermediate office" the trunk line 3 is indicated as terminating in a trunk hunting switch 10 and its associated relay and circuit arrangement whereby this trunk may be connected to an idle trunk such as 11 or 12 of a group 100 105

of trunks outgoing to a distant office. Trunks such as 11 and 12 are multiplied to other trunk hunting switches such as 10, each of which may be associated with a trunk such as 3 leading to and terminating in jacks such as 1 and 2 at office 1. The trunk 6 from office 2 is shown terminating in a trunk hunting switch 15 and the relay and circuit arrangement for the extension of this trunk 6 to trunks such as 11 and 12 is indicated, for the sake of simplicity, by a box marked 16. The switch 15 and its associated relay circuit arrangement 16 is identical with the switch 10 and its relay and circuit arrangement and it should be understood that the outgoing trunks 11 and 12 may be multiplied not only to switch 15 but also to other switches associated with other trunks such as 6 leading to office 2. While only two smaller offices have been illustrated, a larger number of such offices may be similarly equipped and connected through the intermediate office and the outgoing trunks to the distant larger office.

To set forth the operation of this trunking arrangement, it will be explained in the following detailed description of the invention, first, how the system operates when a call from office 1 is to be extended over trunk 3 through the intermediate office by means of switch 10 and its associated relay and circuit arrangement to a distant larger office, and second, how the busy test arrangement common to all the incoming trunks at this intermediate office operates when all of the outgoing trunks are engaged and an operator at office 1 attempts to establish a connection.

If it is assumed then that an operator at a position in office 1 inserts the calling plug of a cord circuit into jack 2, for example, it is well known in the art that the tip terminal of jack 2 will be connected to ground and a circuit will therefore be established as follows: battery, upper make-before-break contact of relay 20, upper winding of relay 21, tip conductor of trunk line 3, tip terminal of jack 2 to ground at the operator's cord circuit. This causes the operation of relay 21 which in attracting its armature closes a circuit for relay 22 as follows: battery, armature and front contact of relay 21, lower make-before-break contacts of relay 20, upper winding of relay 22 to ground. This causes the operation of relay 22 which in attracting its upper armature opens the tip and ring conductors to the switch 10 to prevent interference with a possible other connection over the outgoing trunks terminating at this switch. The operation of relay 22 also closes a circuit for relay 20 as follows: battery, armature and front contact of relay 21, lower inner armature and front contact of relay 22, winding of relay 20 to ground. Relay 20 in operating closes a lock-

ing circuit for itself through its lower middle armature and front contact to the battery at the armature and front contact of relay 21 and also connects at its upper armature and front contact and lower inner armature and front contact the tip and ring leads from trunk line 3 to contacts of relay 22. The operation of relay 20 opens the circuit for the upper winding of relay 22 but the circuit for the lower winding of this relay 22 is now extended from the battery at the armature and front contact of relay 21, through this winding, the lower outer armature and front contact of relay 22 to the hunting brush 25 of switch 10. It should be noted that a parallel path is also established to the hunting brush for the stepping magnet 26 from the battery at the armature and front contact of relay 21, through the lower outer armature and front contact of relay 22. If the switch 10 is resting with its brushes on a busy outgoing trunk, ground from the sleeve lead of this trunk through the hunting brush 25 is supplied for maintaining relay 22 energized. The same ground causes the stepping magnet 26 to operate and in operating interrupt its own circuit so that it will release and step the brushes of switch 10 on to the next trunk terminals. In case the next trunk is also busy and consequently has its sleeve lead grounded, the switch operates again and this action is repeated until the brushes finally come to rest on the terminal of an idle trunk. The hunting brush 25 is so constructed as not to open the circuit to the sleeve terminals when stepping from one terminal to another and the circuit for the lower winding of relay 22 is therefore maintained until the idle trunk is reached. When the switch 10 therefore finally comes to rest on an idle outgoing trunk, the sleeve circuit through the lower winding of relay 22 is broken so that this relay in releasing now completes the connection of the tip and ring conductors from the trunk line 3 through to the tip and ring brushes 27 and 28 of switch 10. It should also be noted that a busy condition is now established on the sleeve terminal of this trunk from ground at the lower outer armature and front contact of relay 20 through the lower outer armature and back contact of relay 22 through brush 25 so that the selected trunk will now test busy to other switches to which its terminals are multiplied. When relay 22 releases, the condition will therefore be such that relay 21 will be maintained energized by having its two windings included in the tip and ring leads of this trunk line 3, and consequently, relay 20 will also be held locked by virtue of the operation of relay 21.

If it is now assumed that all of the trunks such as 11 and 12 leading to the distant larger office are engaged, it will be seen that

on every seizure of a trunk to this office by switches such as 10 or 15, the associated sleeve terminals of these switches will cause the operation of the corresponding relays such as 29 and 30; that is, for example, relay 29 will be operated when trunk 11 is engaged by a circuit from battery, winding of relay 29, through a hunting brush such as 25, lower outer armature and back contact of a relay such as 22, lower outer armature and front contact of a relay such as 20 to ground; while when trunk 12 is engaged relay 30 will be operated over a similar circuit through an associated sleeve terminal and hunting brush to ground at a relay such as 20. In case therefore that all of the trunks to the larger office are engaged, all of the relays such as 29 and 30 will be operated and through a series circuit will cause the operation of relay 31. This circuit may be traced as follows; battery through the winding of relay 31 over a circuit through the armatures and front contacts of relays such as 30, through the armature and front contact of relay 29 to ground. Relay 31 in operating closes a connection from ground through an interrupter 32, the armature and front contact of this relay 31, and therefrom through the circuit of all relays such as 22 of the relay and circuit arrangements associated with switches such as 10 or 15 or other switches at the intermediate office, through condensers such as 33 of the relay arrangement associated with the switch 10 or condenser 34 of the relay arrangement associated with switch 15 and corresponding condensers of other relay and circuit arrangements associated with other switches. That is, if there are twenty outgoing trunks to the larger office, twenty circuits are completed from the ground at interrupter 32 through the twenty condensers such as 33 and 34 of twenty switches such as 10 and 15.

If now an operator, for example in office 1, attempts to establish a connection to the distant larger office by inserting a calling plug in a jack such as 1, the functions hereinbefore described for the operation of relays such as 21, 22 and 20 and stepping magnet 26, of the relay arrangement and switch associated with the trunk selected, will take place. That is, the switch such as 10 would begin hunting for an idle trunk. Upon the operation of a relay such as 22, a circuit will be established from battery through the upper outer armature and front contact of a relay such as 20, and winding of a relay such as 21, tip conductor of a trunk such as 3, tip terminal of a jack such as 1, to the busy test winding of the operator's telephone set of the cord used, as is well known in the art. It will be noted that the circuit from battery through a condenser such as 33 through the interrupter 32 to ground will alternately charge and discharge the condenser 33 at the

rate of interruptions and consequently a tone will pass over the tip side of the trunk to the operator's telephone set. Upon receiving this signal, which is interpreted by the operator, that no trunks outgoing from the intermediate office to the distant larger office are available, the operator will disconnect her cord from the jack such as 1. This disconnection releases the relays such as 21, 20 and 22 and the magnet such as 26 so that the corresponding switch will stop its hunting movement. It should be noted that in case an outgoing trunk becomes idle while the operator is still connected to a jack such as 1 or 2 the corresponding switch will step on the terminals of this idle trunk and relay 22 will release and remove the busy tone from the corresponding incoming trunk. The operator may under these circumstances remain connected and extend the connection further.

If the operator at the position at which jack 1 is located attempts to connect with trunk line 3 and this trunk is already engaged by the operator at the position at which jack 2 is located as through any other jack multiplied to trunk line 3, she will naturally find that it is engaged by listening to the conversation over the trunk carried on by the connected subscriber.

What is claimed is:

1. In a trunk system comprising a large number of jack terminals, corresponding switches and a comparatively smaller number of trunks accessible thereby, means for establishing a busy condition for such jack terminals as are not used in the connections responsive to the engagement of all of said trunks, and means for connecting said busy condition means to the terminals of any idle jack responsive to it being seized while all trunks are engaged.

2. In a straightforward trunking system, groups of trunks incoming from different offices, an individual switch for each trunk at an intermediate office, a single group of trunks outgoing from said switches, smaller in number than the total number of incoming trunks and switches, means associated with each incoming trunk and its switch responsive to the seizing of the trunk for operating said switch to hunt for an idle outgoing trunk, means responsive when all outgoing trunks are engaged for establishing a busy condition for all incoming trunks not in use and means individual to each incoming trunk each responsive to the seizing of the corresponding trunk after the busy condition has been established for indicating at the terminals of said seized trunk such busy condition.

3. In a trunking system, groups of trunks incoming from different offices to an intermediate centrally located office, switches at the intermediate office each associated with

an incoming trunk, a smaller number of trunks available to said switches and outgoing to a distant office, means associated with each incoming trunk for operating the corresponding switch to hunt for and connect said incoming trunk with an idle outgoing trunk, and means for transmitting a busy signal over the incoming trunk the corresponding switch of which is hunting for an idle outgoing trunk if all the outgoing trunks are engaged.

4. In a trunking system, groups of trunks incoming from different offices to an intermediate centrally located office, switches at the intermediate office one for each incoming trunk, a smaller number of trunks available to said switches and outgoing to a distant office, means associated with each incoming trunk for operating the corresponding switch to hunt for and connect said incoming trunk with an idle outgoing trunk, means for transmitting a busy signal over the incoming trunk the corresponding switch of which is hunting for an idle outgoing trunk if all the outgoing trunks are engaged, and means for discontinuing the transmission of the busy signal over said in-

coming trunk if any one of said outgoing engaged trunks become idle during the trunk hunting movement of the corresponding switch.

5. In a trunking system, incoming trunks, a smaller number of outgoing trunks, switching means associated with each incoming trunk and responsive to the seizing thereof for hunting for and connecting the seized incoming trunk with an idle outgoing trunk, means for transmitting a busy signal to any incoming trunk when seized responsive when all of said outgoing trunks are engaged by other incoming trunks, means for discontinuing the busy signal to said seized incoming trunk if any of the outgoing trunks become idle while said incoming trunk is still seized and means for continuing the trunk hunting movement of the corresponding switching means of said seized incoming trunk after the busy signal is discontinued and until the idle outgoing trunk is found.

In witness whereof, I hereunto subscribe my name this 7th day of July A. D., 1925.

WILLIAM H. MATTHIES.

DISCLAIMER.

1,600,556.—*William H. Matthies, Hackensack, N. J. STRAIGHTFORWARD TRUNKING SYSTEM.* Patent dated September 21, 1926. Disclaimer filed September 29, 1928, by the assignee, *Western Electric Company, Incorporated.*

Hereby enters this disclaimer to the said claim of said Letters Patent which is in the following words, to wit:

“5. In a trunking system, incoming trunks, a smaller number of outgoing trunks, switching means associated with each incoming trunk and responsive to the seizing thereof for hunting for and connecting the seized incoming trunk with an idle outgoing trunk, means for transmitting a busy signal to any incoming trunk when seized responsive when all of said outgoing trunks are engaged by other incoming trunks, means for discontinuing the busy signal to said seized incoming trunk if any of the outgoing trunks become idle while said incoming trunk is still seized and means for continuing the trunk hunting movement of the corresponding switching means of said seized incoming trunk after the busy signal is discontinued and until the idle outgoing trunk is found.”
